DESIGN FOR A FLUORESCENT LIGHTING FIXTURE

Oswald W. Klingsick, Richmond Heights, Mo., as-
signor to Day-Brite Lighting, Inc., St. Louis,
Mo., a corporation of Missouri

Application September 28, 1940, Serial No. 95,477

Term of patent 14 years

To all whom it may concern:

Be it known that I, Oswald W. Klingsick, a citizen of the United States and a resident of the city of Richmond Heights, in the county of St. Louis and State of Missouri, have invented a new, original, and ornamental Design for a Fluorescent Lighting Fixture, of which the following is a specification, reference being had to the accompanying drawing, forming part thereof.

Fig. 1 is a perspective view, as seen from below, of a fluorescent lighting fixture showing my new design,

Fig. 2 is a top plan view thereof,
Fig. 3 is a side elevational view of the fixture shown in Fig. 1,
Fig. 4 is a bottom plan view of the same; and
Fig. 5 is an end elevational view thereof.

I claim:

The ornamental design for a fluorescent lighting fixture, as shown.

OSWALD W. KLINGSICK.
